UNITED STATES PATENT OFFICE

2,441,332

METHOD AND MEANS FOR BLOCKING HATS

Adolph Reinsberg, Chicago, Ill.

Application February 5, 1946, Serial No. 645,773

4 Claims. (Cl. 223—12)

1

The present invention relates to the blocking of headgear such as common hats and caps, and more particularly to the blocking of headgear in production manufacture, but it does have application in reblocking of hats.

In the present description, and in reference to the present invention, the term "hat" is used hereinafter in its generic sense for headgear of numerous varieties, including crowns without visors or brims, crowns with visors such as caps, and crowns with brims such as men's hats.

In the production of hats, material is pre-shaped, as in the case of caps, where fabric parts are sewed together to form the crown. Then the pre-shaped crown must be suitably blocked to press out any wrinkles or seams and otherwise present a smooth finished appearance to the hat. Numerous methods have been employed heretofore to accomplish these purposes. The present invention provides a device which permits blocking of hats to be accomplished with great rapidity, with small effort on the part of an operator, and with a minimum of danger of burning the operator, or the hat.

It is the general object of the invention to provide a device to block hats with speed and facility.

It is another object of the invention to provide a heated form having a temperature above the boiling point of water, and means to stretch or smooth a moistened hat onto said form and hold it in that condition while it is being blocked.

It is another object of the invention to provide a heated form through which steam may be admitted for a short interval of time to steam the hat as a step in the blocking process.

It is a particular object of the invention to provide a device with pedals for controlling the discharge of steam and for operating the hat-clamping means.

Numerous other and ancillary objects and advantages of the invention will become apparent from the following description and explanation of the invention as shown in the accompanying drawings in which:

Fig. 1 is a perspective view of an exemplary device ready to receive a hat.

Fig. 2 is a cross-section showing the bottom and pedal structure taken on the line 2—2 of Fig. 1.

Fig. 3 is a vertical cross-section of the upper portion taken through the center of the device on line 3—3 of Fig. 4.

Fig. 4 is a horizontal cross-section near the

2

top of the device taken on the line 4—4 of Fig. 3 looking downwardly.

It is to be understood that the device as illustrated in the drawings is merely exemplary of the invention and that the invention is not limited to or by the particular device illustrated.

The present invention is explained by reference to caps. First a cap is moistened and the dampened cap smoothed onto a heated form. 10 The moisture is preferably provided by steaming the cap, and preferably the steam issues from the form on which the cap is blocked. A cap to be blocked is merely positioned on a form made to fit the interior of the cap, and then a blast of 15 steam from the form is shot into the cap, thus moistening the cap. In preferred practice the cap, with or without a lining, is a little scant in size to fit the block for it, requiring the cap to be stretched slightly to fit the block. But because the block is very hot, it is not safe for an 20 operator to do this with bare hands. The operator manipulates the device to move clamping and holding means onto the moistened cap as it is resting over the form, said means being also 25 capable of stretching the cap if need be, thereby to smooth and shape the cap on the form. The form is highly heated, and the heat dries the moisture from the stretched hat quickly and almost instantaneously so that the cap may be 30 readily and quickly removed from the form as a blocked cap.

I have found in attempts to introduce steam to a hat through a hat-block by certain constructions thereof, including that illustrated in the 35 drawings, there are practical objections. For one, there is condensate which collects in the block, unless special means are provided to lead it away. The condensate may arrive with the steam, or form in the block. The amount of 40 condensate may vary in the time intervals between active discharges of steam. This condensate is in part or in entirety, depending upon conditions, blown with the steam into the hat. No regularity in the degree of moistening can be 45 achieved.

In accordance with one feature of the present invention, the hat-block is heated to a temperature above the boiling point of water, thus to avoid, or to boil off, condensate and maintain a 50 dry steam chamber in the block.

Various means may be employed so to heat the form, not only to dry the steam chamber where such is present, but also to cause the form to dry out the moistened hat, whether or not the moistening is effected by steaming

through the block. A heated block, at a temperature below the boiling point of water, effects only a slow evaporation. A block temperature above the boiling point, and safe for the particular material, effects a rapid and almost instantaneous drying and blocking.

Numerous expedients may be adopted to moisten or steam the headgear to be dried. These may be apart from the device, or incorporated into the device, preferably in the manner hereinafter described.

Since it is not safe or practicable for an operator to hold the headgear onto a form sufficiently hot that it will quickly dry moist material, there is provided a mechanical holding device. This is specially constructed to be complementary to a particular hat or to a form conforming to some particular headgear placed on the form. The particular design of the holding means will vary according to the character of the headgear or according to particular preference. It is such as to assure that the steamed headgear is adequately and properly held smoothly on the form while it is being dried or blocked.

The form of the invention particularly illustrated in the drawings has a standard comprising four legs 10 made of an angle iron, and suitably braced by the cross-brace 11 at the front and near the floor, and by three other braces 12, 13 and 14 between the legs 10 at a more elevated position from the floor.

A rod 15 serves as a pivotal shaft support, being mounted horizontally at the rear of the machine above the cross-brace 13. Two foot pedals 16 and 17 are pivoted on the rod 15. The pedal 16 is mounted on an arm 18 of which the rear end has a cylindrical head 19 serving as a bearing on the rod 15. A spring 20 is connected to the arm 18 and extends upwardly to a finger 21 projecting inwardly from the cross-brace 12. The spring urges the pedal 16 upwardly and thereby operates a connecting rod hereinafter described which controls a supply of steam.

The pedal 17 is connected by two arms 23 and 24 which together form a fork which carries at its open end a cylindrical head 25 pivoted on the rod 15. A link 26 is connected pivotally between the two arms 23 and 24, and extends upwardly for operating clamping, or stretching and clamping means, later described.

The legs 10 have a table top 30 which provides a foundation upon which to secure the hat-form. As shown in Figs. 1, 3 and 4, the hat-form is a substantially hollow dome-shaped form 31, made to fit cap snugly and preferably made of aluminum. A cap 32 is shown in Figs. 3 and 4, and has a crown portion 33 and a visor 34. The bottom of the dome 31 has a flange portion 35, which serves in part as a reinforcement to maintain the form in its desired shape. Secured to the flange 35 are two pairs of legs 36 and 37. The pair of legs 36 merely rests upon the table top 30. The other legs 37 are similar to the legs 36, but are secured to the table top by angle iron connections 38 which have screws 39 into the legs and anchor bolts 40 riding in slots 41 in the table top, thus to permit forward and rearward adjustment of the form 31 with respect to the rear portion of the clamping means. By this adjustment hat material of various thicknesses may be accommodated.

Within the space between the legs 36 and 37 there is mounted a gas burner 42 on a gas supply line 43 having shut-off valve 44. The burner is secured to the table top 30 by a suitable bracket 78

means such as that illustrated by 45. The gas flame plays on a steam chamber in the form 31.

Transversely of the interior of the form 31 there is a partition 48 providing a chamber 49 at the top of the dome. Numerous pinholes 50 through the dome act as steam-jet openings communicating from the chamber 49 to a hat placed on the form. The partition 48 has a tapped opening 51 therein, into which is threaded a short length of pipe 52 carrying at its end above the table top, one portion of a union 53. The other portion of the union 53 is connected to a length of pipe 54 passing through the table top 30 and beneath the table connected to a valve 55 located in steam supply line 56. Pipe 54 is movable with the form 31 by reason of a slot 57 in the table top 30, covered by a collar plate 58 carried by the pipe 54. The valve 55 has a fixed bracket 59 to which is pivoted an operating arm 60 connected by link 61 to the arm 18 carrying pedal 16. The valve operating arm 60 has a finger 62 which presses pin 63 to open the valve for passing steam when pedal 16 is depressed.

Above the table top there is a bracket to which is pivoted a carrier for the clamping means, and the carrier is operated by the said link 26 in turn operated by the second pedal 17. The bracket is formed by two arms 65 and 66 each welded or otherwise secured at one end to the table and each approaching the other at the other ends 67 and 68, respectively. These ends carry a connecting pin 69 between them serving as a pivot for an arm or lever 70 swinging in a vertical plane. Lever 70 extends forwardly toward the block, and when generally horizontal is in hat-holding position. At the forward end of the lever 70 there is a yoke-shaped finger 71 with a leather lining 72, which clamps one side of a hat. An adjustably positioned yoke 73 is carried by and extends vertically from the lever 70 over the form to the front side thereof, at which the end 74 of the yoke 73 carries an adjustable plate 75 mounted by slot and screw structure 76. The plate 75 carries a yoke-shaped finger 77 with leather lining 78 complementary to the yoke-shaped finger 72 to hold the hat on the forward side. Any suitable mounting, such as 79, holds yoke 73 adjustably mounted on lever 70. The operating link 26 from the pedal 17 is connected to the forward side of lever 70 and pivoted thereto at 80. The rear arm of lever 70 carries a spring 81 in tension between it and the link 26. Thereby the spring 81 urges the rear arm of lever 70 and the link 26 to close about their pivot 80. This urges the pedal 17 upwardly and urges the holding means 71 and 77 away from engagement with the cap shown.

In operation, the operator places a hat, such as the cap shown, loosely over the form, and at the same time depresses the pedal 16. This gives a shot of dry steam to the cap and sufficiently moistens it. Then as the moisture equalizes itself in the fabric the operator depresses pedal 17 against the urge of spring 81 while at the same time adjusting the cap into ultimate form to be held by the mechanical fingers.

In the case of a cap it is preferred that the relative sizes of the form and of the unblocked cap be such as to require the mechanical fingers and clamping means to stretch the cap onto the form. This results in stretching the cap-material locally in varying degrees and thereby truly shaping the cap. Where a lining is present, this also is shaped or stretched if required, to nest neatly with the cover. Having stretched

the cap on the form, the operator retains the pedal 17 in depressed condition while the heated form 31 effects almost instantaneous drying of the cap sufficiently to leave it in blocked condition when removed. In the meantime the operator's hand are free to prepare the next cap for placement on the form. When the cap is ready for removal clamp 17 is allowed to rise by action of spring 81, the blocked hat is removed, and the cycle is repeated.

The device in operation as described brings many times more pressure on the stretching of the cap over a block, and gives a more uniform stretching, than the old-style hand-blocking with wooden blocks.

From the foregoing it will be appreciated that numerous changes and modifications may be made in the device without departing from the invention set forth in the appended claims.

I claim:

1. In a hat blocking machine, in combination: a hollow dome of metal conforming to the desired shape and having a continuously convex outer working surface; an upper portion of said dome having small perforations to permit exit of steam or other gases; a partition below said perforated portion defining a steam chamber, the walls of which include said perforated portion; said dome extending down beyond said partition to define a deep downwardly opening bowl; pipe connections for delivering live steam through said partition into said chamber; a constantly operating gas burner in said bowl near the upper portion thereof for heating said bowl and partition directly and the remainder of said dome by conduction through the metal; stretching fingers shaped to partially encircle said dome at front and back, and movably mounted to move down and force a hat over said dome by contact only and by engaging the peripheral edge portions only of a hat positioned over said dome, leaving the rest of said hat directly exposed to atmosphere; a support holding said dome in position for easy access to a standing operator; connections between said support and dome for adjusting the position of said dome to secure effective engagement with one of said stretching fingers; means for adjusting the other of said fingers to the adjusted position of said dome; two control pedals, each normally elevated and in position to be conveniently depressed by the foot of an operator standing in front of said dome; connections between one pedal and said pipe connections for delivering steam only as long as the operator holds the pedal down, and connections between the other pedal and said stretching fingers for actuating said stretching fingers into stretching position with a variable force controllable by the pressure of the operator's foot.

2. In a hat blocking machine, in combination: a hollow dome of metal conforming to the desired shape; an upper portion of said dome having small perforations to permit exit of steam or other gases; a partition below said perforated portion defining a steam chamber, the walls of which include said perforated portion; said dome extending down beyond said partition to define a deep downwardly opening bowl; pipe connections for delivering live steam through said partition into said chamber; a constantly operating gas burner in said bowl near the upper portion thereof for heating said bowl and partition directly and the remainder of said dome by conduction through the metal; stretching fingers

shaped to partially encircle said dome at front and back and movably mounted to move down and force a hat over said dome by contact only and by engaging the peripheral edge portions only

5 of a hat positioned over said dome, leaving the rest of said hat directly exposed to atmosphere; a support holding said dome in position for easy access to a standing operator; and connections for actuating said stretching fingers into stretching position with a variable force controllable by the operator.

10 3. In a hat blocking machine, in combination: a hollow dome of metal conforming to the desired shape; a portion of said dome having small perforations to permit exit of steam or other

15 gases; walls defining a steam chamber which includes said perforated portion; stretching fingers shaped to partially encircle said dome at front and back and movably mounted to move down

20 and force a hat over said dome by contact only and by engaging the peripheral edge portions only of a hat positioned over said dome, leaving the rest of said hat directly exposed to atmosphere; and connections for actuating said stretching fingers into stretching position with a variable force controllable by the operator.

25 4. In a hat blocking machine, in combination: a hollow dome of metal conforming to the desired shape and having a continuously convex outer working surface; an upper portion of said dome having small perforations to permit exit of steam or other gases; means for heating said dome; stretching fingers shaped to partially encircle said dome at front and back and movably

30 mounted to move down and force a hat over said dome by contact only and by engaging the peripheral edge portions only at a hat positioned over said dome, leaving the rest of said hat directly exposed to atmosphere; operator-controlled means for delivering steam into said dome and through said perforations; and connections for actuating said stretching fingers into stretching position.
